Francis Hovey

Francis Harvey, of New York, N.Y.

Letters Patent No. 2231-Dated Dec. 12-1865.

Design for the Arch of a Letter Press.

The schedule referred to in these Letters Patent and making part of the same.

To all whom it may concern:

Be it known that I, Francis Harvey, of the City, County and State of New York, have invented a new design for the Arch of a Letter Copying Press; and I do hereby declare the following to be a full, clear, and exact description of the same, reference being had to the accompanying drawings, forming a part of this specification, and in which:

Figure 1. is a side elevation of my design.

Figure 2. is a half plan of the same.

Similar letters of reference indicate corresponding parts in both figures.

The general form of my design is that of an arch formed of the figures herein described.

On each side of the central hub A, the arch is formed of the figure of a dolphin, the head being down upon the base C, and the body rising with a curve, as represented in figure 1 of the drawing. At portion of the body nearest the tail is turned once around in a downward direction, and the tail runs out horizontally and branches off to join the hub A, embracing it on each side of the said hub which is cylindrical. Extending from about the centre of the back of the dolphin on each side, is a braid or double cord B, which is arched and united with the hub A, or near the top.

What I claim as my invention and desire to secure by Letters Patent is:

The design and configuration of the arch herein described and represented by the accompanying drawings.
